SAFETY RAFT SLIP LOCK

Johan Frederik Carlsen, Brooklyn, N. Y.

Application October 31, 1942, Serial No. 464,022

5 Claims. (Cl. 9—23)

This invention relates to safety raft slip locks which are devices for automatically releasing safety life rafts from ships in the event of torpedoing or sinking from other reasons at sea, and specifically it refers to an improved slip lock which is automatically opened by a float as soon as the float is submerged in water.

Slip locks of the present type have been known for some time and consist of a pivoted hook or latch which is slipped through an eye and fastened in such a way that it is only necessary to slip off a locking member and thereby releasing the hook or latch. Due to the fact, however, that this locking member may accidentally come loose and thereby cause the loss of the life raft at sea, it is common practice to secure same by means of a seizing which has to be cut off before the slip lock can be opened. Recent experience has shown, however, that in torpedoings where the ship is liable to sink in very short time the crew usually runs directly for the life boat and no one will take time off to run forward or aft to unloosen the life rafts. For this reason it had often happened that the life rafts have gone down with the ship and the boats may have been damaged and sunk thereby preventing the rescue of the members of the crew who had to jump in the ocean.

The object of my present invention, therefore, is to provide a safety raft slip lock which will automatically release the raft when the ship sinks.

Another object of my invention is to provide a slip lock which can be adapted to and fitted over the devices presently available thereby making the installation simpler and furthering the adaption of this life saving device.

Still another object of my invention is to provide a device which is simple to manufacture and of low cost and which is safe and effective in operation.

Other objects and advantages of my invention will be apparent during the course of the following description.

In the accompanying drawings, forming a part of this specification, and in which like numerals are employed to designate like parts throughout the same,

Figure 1 is a side elevation of a life raft having a slip lock in its closed position embodying my invention,

Figure 2 is a side elevation of the same life raft as shown in Figure 1, but in open position,

Figure 3 is an enlarged side view of the slip lock in closed position,

Figure 4 is an elevation along line 4—4 in Figure 3,

Figure 5 is a section along line 5—5 in Figure 3,

Figure 6 is a section along line 6—6 in Figure 3, and

Figure 7 is a side elevation of a slip lock such as used today without my invention.

In the drawings, wherein for the purpose of illustration, is shown a preferred embodiment of my invention, the numeral 10 designates a life raft or safety raft of the type commonly used on cargo vessels and usually carried in rigging in the fore and aft masts, one on each side of each mast. The life raft 10 is held against the stays 11 by means of the rope 12 which extends from ring 13 to eye 14. The eye 14 connects rope 12 to link 15. The hook member 16 is pivoted around the lower end of the link 15 and held in its closed position by the slip ring 17. The hook member 16 is engaged with the chain 18 and this arrangement, as described supra, constitutes the present slip lock as used on most ships, see Figure 7. To prevent the slipping off of the ring 17, a seizing 19 is placed around link 15 above the ring 17 and this seizing has to be cut or unraveled to permit the opening of the latch member 16.

My improved device, as shown in Figures 1, 2, 3, 4, 5 and 6, consists of a double latch 19 which is pivoted on bolt 20 and held together at one end by bolt 21. The bolt 20 is welded to a clamp member 22 which is fastened to link 15 by means of clamp 23 and bolt 24. The latch members 19 have a hook 25 at one end which fit over ring 17 thereby effectively locking same in place. The clamp members 22 and 23 may be adjusted upward or downward on link 15 thereby placing the members 19 in the most suitable position locking ring 17, see Figure 3.

The latch members 19 are preferably made from sheet metal and are bent together at one end and held in place by bolt 21 so as to form a lever pivoted on bolt 20, see Figure 5. Pivoted on bolt 21 and placed in a position between the two latch members 19 is a lever 26 which on one end carries a knife edge 27 and which has a rope 28 attached to its other end. The lever 26 also has stop pins 29 and 30 which will limit its rotation by striking against latch members 19. The rope 28 is connected with one end to float 31 which is preferably supported in a suitable manner on top of the life raft 10. The support of float 31 is arranged so that it is free to float up if submerged in water.

The chain 18 may be fastened to the deck 32 or to the rail 33 and it is obvious that this method of fastening can be arranged in many different ways. It is also obvious that the principle of the float-operated latch, as illustrated by members 19, lever 26, rope 28 and float 31, is subject to many variations in various applications of this principle. I do not wish to be limited to the exact form or shape disclosed in the drawings.

The operation of my invention is as follows:

Assuming that the old type slip lock is present, as illustrated in Figure 7, my new device is fitted on same by fastening clamps 22 and 23 on link 15 by means of bolt 24 and adjusted to a position where the hooks 25 will retain the ring 17 in a suitable position when the latch members 19 are in the extreme downward position, as indicated in Figure 3. To secure the latch members 19 in the locked position and prevent accidental opening of the same and loss of the life raft, a seizing 34 is placed around the members 19 and the hook 16. This seizing 34 is preferably made with manila yarn or twine and is pulled tight so that the knife edge 27 will easily cut same when the rope 28 pulls lever 26 upward. When an emergency arises, the float 31 will float up and give a sudden pull on rope 28 which for that reason has a slack, as indicated in Figure 1. This sudden pull will cut off the seizing 34 and thereby free the latch members 19 and simultaneously lever 26 has been pulled upward until stop 39 hits member 19. The lever 26 and members 19 will now form one lever with fulcrum on bolt 20 and the pull of rope 28 will move this lever upward, thereby swinging hook 25 out of engagement with ring 17 and the curved cam surface 19a will push ring 17 upward until the hook member 16 is released. The chain 18 will then drop off, as indicated in Figure 2 and rope 12 is released, thereby releasing the life raft 10 without any attention or special action of the crew.

It is to be understood that the form of my invention, herewith shown and described, is to be taken as a preferred example of the same and that various changes in the shape, size and arrangement of parts may be resorted to, without departing from the spirit of my invention or the scope of the subjoined claims.

Having thus described my invention I claim:

1. A safety raft slip lock of the character described, comprising a link, a hook hinged on said

link, a slip ring locking said hook to said link, and float operated latching means whereby said slip ring may be automatically moved out of engagement with said hook thereby releasing same.

5 2. A safety raft slip lock of the character described, comprising an elongated link; a hook member hinged to said link, a slip ring slidable on said link whereby said hook member may be locked in its closed position and float operated latch member adjustably fastened to said link, whereby said slip ring may be automatically moved out of engagement with said hook thereby releasing same.

15 3. A safety raft slip lock of the character described, comprising an elongated link; a hook member hinged at one end to said link, a slip ring slidable over said link whereby said hook may be locked in its closed position; a latch member adjustably fastened to said elongated link, said latch member having a hook at one end fitting over said slip ring and a curved cam surface adjacent to said hook; a lever pivoted at one end of said latch member, said lever having a knife edge on one end and being fastened with its other end to a float whereby said float may operate said lever and said latch members thereby releasing said hook.

20 4. A safety raft slip lock of the character described, comprising an elongated link, a hook member hinged at the lower end of said link; a slip ring slidable over said link whereby said hook member may be locked in its closed position; a pair of latch members adjustably fastened to said link, said latch members having a hook at one end fitting over said slip ring and curved cam surface adjacent to same; a lever pivoted at the other end of said latch member, said lever having a knife edge on one end and stop pins engageable with said latch members, 25 and a float attached to the other end of said lever whereby same may be operated thereby opening the slip lock.

25 5. A safety raft slip lock of the character described, comprising an elongated link; a hook member hinged to said link, a locking ring slid- 30 able on said link whereby said hook may be held in its closed position and float operated latching means whereby a seizing may be automatically cut and said locking ring moved out of engagement with said hook thereby opening same.

JOHAN FREDERIK CARLSEN.
